SPRING FORMING DEVICE

Charles R. Bergevin, Torrington, Conn., assignor
to The Torrington Manufacturing Company,
Torrington, Conn., a corporation of Connecticut

Application October 26, 1937, Serial No. 171,120

10 Claims. (Cl. 140—103)

The present invention relates to a device for forming or bending wound springs of the type commonly known as torsion springs, i. e., springs having coiled bodies of different lengths and diameters, with their projecting ends formed or bent to suit various purposes for which the springs may be used. The object of the present invention is to provide an improved device of the above indicated character, which, by its operation, is adapted to form bends of different degrees at any desired angle to the axis of the coiled body of a spring. The device of the present invention is particularly characterized by an angularly adjustable head carrying a number of forming tools, independently controllable from a central driving element within the head, so as to perform bending operations on the end of a spring, in any desired sequence. These forming tools operate at an angle to the axis of the wire portion being formed, thereby making it possible to form complicated bends without interference between the working portions of the tools. The above and other advantageous features of the invention will hereinafter more fully appear from the following description, considered in connection with the accompanying drawings, in which:—

Fig. 1 is a view in front elevation, of a forming device embodying the invention.

Fig. 2 is a view partially in horizontal section, and partially in plan, of the device of Fig. 1.

Fig. 3 is a vertical sectional view along the line 3—3 of Fig. 2, looking in the direction of the arrows.

Figs. 4 and 5 are diagrammatic views, illustrating the functioning of one pair of forming tools.

Fig. 6 is a diagrammatic view of a further step in the forming operation, as viewed from the front of the device.

Figs. 7 and 8 are diagrammatic views, illustrating the functioning of the tools shown in Fig. 6, as viewed in plan.

Fig. 9 is a view, in perspective, of a completed spring having an end formed by the device of the present invention.

Fig. 10 is a fragmentary view of a tool slide actuator.

Like reference characters refer to like parts in the different figures.

Referring first to Figs. 1 and 2, the forming device consists of a base 1, providing upwardly extending arms 2, between which a bracket 3 is mounted. The bracket 3 is secured to the arms 2 by bolts 4 threaded into the bracket, the

bolts 4 passing through slots 5 in the arms 2, whereby the bracket 3 may be clamped in different positions. Studs 6 threaded through lugs 7 provided by the bracket 3, bear on the upper surfaces of the arms 2 and provide means for closely adjusting the vertical position of the bracket 3 when the bolts 4 are loosened.

The bracket 3 provides a cylindrical opening 8, in which is received a drum 9 carrying a forming tool head 10, which projects beyond the opening 8, and is secured to the front end of the drum 9 by screws 11, see Fig. 1. The drum 9 carrying the head 10 and other associated parts, hereinafter described, is angularly adjustable within the bracket 3 about the axis of the opening 8. In order to clamp the drum 9 and the head 10 in any desired angular position, the bracket 3 provides a set screw 12, accessible from the top of the bracket, the end of which is received in a groove 13 extending around the periphery of the drum 9.

The drum 9 provides a central opening 14, in which is received a sleeve 15, extending rearwardly through the bracket 3, and carrying bearings 16, on which is rotatably mounted a sleeve 17 carrying a number of cams 18, 19, 20 and 21, as best shown in Fig. 2. A pinion 22 is also mounted on the sleeve 17, and is in mesh with a gear 23 mounted on a stud 24 carried by an arm 25 secured to the base 1 at 26, so that the stud 24 is fixed with respect to the rotatable cam sleeve 17. The gear 23 is adapted to be driven from any suitable source of power, not shown, so as to rotate all of the cams 18, 19, 20 and 21 in unison.

The central drum sleeve 15 provides an opening 15a, in which is received a wire guide 27 and a cutting tube 28, which extends into the tool head 10 and terminates in a conical nose 28a. Wire 29 extends through the guide 27 and the tube 28, and is adapted to be wound into a spring S in any suitable manner, as by means of a rotatably driven winding arbor 30, see Fig. 4. When a spring S has been wound, as shown in Fig. 2, a straight portion S' extends between the coiled body of the spring and the cutting nose 28a, and it is the function of the device of the present invention to sever the spring S from the wire 27, and to suitably form its end portion S'.

For this purpose, the head 10 carries a group of forming tools 31, 32, 33 and 34, which are actuated by the cams 19, 21, 20 and 18, respectively, so as to perform a predetermined sequence of forming operations, hereinafter described. Each

tool is adjustably mounted in a slide 35, movable on the head 10 by mechanism, shown in Fig. 2, with relation to the particular cam 18 which operates the slide 35 carrying the tool 34. It is obvious, however, that each tool slide 35 is driven in the same manner by its associated cam, so that it is unnecessary to describe in detail the mechanism for driving each individual tool slide.

Each tool slide 35 is movable between radial ways 36 provided by the head 10, and a spring 37 serves to yieldingly maintain a lug 38, provided by the slide, in engagement with a ball 39 carried at the offset end of a crank arm 40, forming part of a shaft 41, as shown in Fig. 10. The shaft 41 is rotatably mounted in an opening 42, extending through the drum 9, and the opposite end of the shaft 41 carries an arm 43 carrying a roller 44 in engagement with the cam 18. It is obvious from a consideration of Fig. 3, that rotation of the cam sleeve 17 will cause the projection 18a of the cam 18 to turn the shaft 41, and thereby cause the ball 39 at the end of the crank arm 40 to move the tool slide 35 in the direction of the end portion S' of the spring S. In considering such movement of the tool slide 35, it should be noted that the projecting face of the head 10 is conical in form, so that the ways 36 are parallel to the surface of the cutting nose 28a, and consequently each tool travels in a line, making an acute angle to the axis of the wire 29. This angularity of the tools is an important factor in the facility with which the end of a spring may be bent into different forms by a sequence of operation of the tools, as will now be described with reference to Figs. 4 to 8, inclusive.

Referring first to Fig. 4, the tools 31 and 32 are shown in the positions which they occupy with reference to the tube 28 at the start of the sequence of tool operations, which results in forming or bending the straight portion S' of the previously wound spring S. Rotation of the cam sleeve 17, starting from the position of Fig. 3, first causes the cam projection 19a to move the tool 31 to the dotted line position, where it remains for an appreciable period, during which the other tools function. Cam projection 21a then causes the tool 32 to move in the direction of the arrow, thereby severing the wire 29 at the nose 28a, the then stationary tool 31 serving to support the wire beyond the nose, as the cutting takes place.

Continued rotation of the cam sleeve 17 then causes the tool 32 to move into the position of Fig. 5, with the tool 31 remaining in its position, in engagement with the wire, thereby imparting a bend to the free end of the coil portion S'. While the portion S' is shown as having had a substantially 90° bend imparted thereto by operation of the tools 31 and 32, obviously, the degree of bend can be varied to be more or less than 90° by altering the inclination of the tool faces. In determining the angle of bend, the fact that the tool slides 35 move at an angle to the axis of the wire, makes it possible to bend the wire at either an acute or an obtuse angle, as desired, a result impossible of accomplishment were the tools to be moved only at right angles to the wire axis.

Following the formation of the bend shown in Fig. 5, the cutting and forming tool 32 is retracted, as shown in Fig. 6, while the tool 31 remains in the position shown. The cam projection 18a then causes the tool 34 to engage the spring portion S at an appreciable distance from the bend, which movement is accompanied by movement of the tool 33 in the direction of the arrow, so that its end will engage the spring portion S' in the

plane of the wire 29, at a point adjacent the previously formed bend, as shown in Fig. 7.

Continued rotation of the cam sleeve 17 then moves the tool 33 into the position of Fig. 8, with the anvil tools 31 and 34 remaining stationary. This final movement of the tool 33 imparts a second bend to the spring portion S' around the end of the then stationary tool 34. In other words, the vertically extending previously bent portion is swung in an arc about the end of the tool 34, to impart a second bend in a plane at right angles to the first bend. The completed spring then appears as shown in Fig. 9.

While, as shown in Figs. 5 and 8, the bends formed in the spring portion S' lie in substantially vertical and horizontal planes with respect to the horizontally extending portion S', the planes of these bends can be readily changed without changing the several tools. As previously pointed out, the cylindrical drum 9 is adjustable angularly within the opening 8 of the bracket 3, upon loosening the clamping screw 12, and so by rotating the entire tool assembly with the drum 9, the planes of the bends can be altered as desired. Furthermore, each tool 31 to 34, inclusive, is adjustable within its slide 35, by means of a screw 45 threaded into the slide 35 and received in a slot 46 provided in the tool. Upon loosening the screw, small adjustments of a tool can be made to suit the diameter of the wire 29, the final position of the tool being determined by a backing stud 47 threaded into a portion of the slide 35. When it is desired to line up the wire guide 27 and cutting tube 28 with the arbor 30 of a spring winding machine, vertical adjustment of the wire axis can be obtained without disturbing the setting of the tools by means of the adjusting studs 6, with the bracket 3 being finally clamped in adjusting position by the bolts 4.

I claim,

1. In a device of the class described, means for supporting a wire, a head surrounding said wire supporting means, a plurality of tools mounted on said head for movement at different angles with respect to said wire, and means symmetrically arranged about the wire axis and carried by said head for separately actuating said tools and performing a sequence of bending operations on said wire.

2. In a device of the class described, means for supporting a wire, a head surrounding said wire supporting means, a plurality of tools mounted on said head for movement at different angles with respect to said wire, and means symmetrically arranged about the wire axis and carried by said head for separately actuating said tools and causing them to first cut and then perform a succession of bending operations on said wire.

3. In a device of the class described, means for supporting a wire, a head surrounding said wire supporting means, a plurality of tools mounted on said head for movement at different angles with respect to said wire, and means symmetrically arranged about the wire axis and carried by said head for separately actuating said tools and performing a sequence of bending operations on said wire, said head, tools and actuating means being adjustable about the axis of said wire to vary in unison the angular relation of all of said tools with respect to said wire.

4. In a device of the class described, means for supporting a length of wire, a head providing guideways radiating from the axis of said wire, tools mounted in said guideways, and means carried by said head for successively imparting move-

- ment to said tools for engaging and bending said wire, said head being adjustable about the axis of said wire to simultaneously shift all of said guideways and tools about the wire axis.
5. In a device of the class described, a wire guide, a head surrounding said guide providing guideways radiating from the axis of a wire in said guide, tools movable in said guideways, a member rotatable on said head about the wire axis and means carried by said head and symmetrically arranged above the wire axis to be operated from said member for actuating said tools in sequence to perform successive bending operations on said wire. 5
10. In a device of the class described, a wire guide, a head surrounding said guide providing guideways radiating from the axis of a wire in said guide, tools movable in said guideways, a member rotatable on said head about the wire axis, a series of cams mounted on said member and connections carried by said head and symmetrically arranged about the wire axis to extend between said cams and said tools for causing said tools to perform a series of bending operations on said wire. 10
15. In a device of the class described, a wire guide, a head surrounding said guide providing guideways radiating from the axis of a wire in said guide, tools movable in said guideways, a member rotatable on said head about the wire axis, a series of cams mounted on said member and connections carried by said head and symmetrically arranged about the wire axis to extend between said cams and said tools for causing said tools to perform a series of bending operations on said wire. 15
20. In a device of the class described, means for supporting a wire, a head providing guideways radiating from said wire at an acute angle to the axis of said wire, tools in said guideways and means for causing said tools to perform a succession of operations on said wire. 20
25. In a device of the class described, means for supporting a wire, a head providing guideways radiating from said wire at an acute angle to the axis of said wire, tools in said guideways and means carried by said head and symmetrically arranged about the wire axis for causing said tools to perform a succession of bending operations on said wire, with said tools engaging said wire at an acute angle to its axis. 25
30. In a device of the class described, a wire guide, a head surrounding said guide providing guideways radiating from the axis of a wire in said guide, tools movable in said guideways, a member rotatable on said head about the wire axis and means operated from said member for actuating said tools in sequence to perform successive bending operations on said wire. 30
